UNITED STATES PATENT OFFICE.

GEORGE C. CUMMINGS AND JOHN A. KICK, OF WESTERN SPRINGS, ILLINOIS.

SYSTEM FOR TRANSMITTING INTELLIGENCE.

1,000,078.

Specification of Letters Patent. Patented Aug. 8, 1911.

Application filed June 16, 1909. Serial No. 502,526.

To all whom it may concern:

Be it known that we, GEORGE C. CUMMINGS, a citizen of Canada, and a subject of King Edward VII, and JOHN A. KICK, a citizen of the United States, residing at Western Springs, in the county of Cook and State of Illinois, have invented certain new and useful Improvements in Systems for Transmitting Intelligence, of which the following is a full, clear, concise, and exact description, reference being had to the accompanying drawings, forming a part of this specification.

Our invention relates to a system for transmitting intelligence, and its objects and advantages will appear.

The invention, in the preferred embodiment, employs an electro-magnetically operated typewriter at the receiving station. At the transmitting station, we employ means for impressing upon the line the current of wave form, which is preferably an alternating current, and there are selecting keys at the transmitting station adapted to select and occasion modification of certain selected waves, whereby apparatus at the receiving station, peculiarly responsive to the waves of modified form may be selected and operated.

In the preferred embodiment of the invention, we employ current wave-modifying means adapted to operate substantially throughout the period occupied in the formation of the wave to be modified and serving to restrict the action of the modifying means to such period. At the receiving station, we employ a plurality of receiving devices, and preferably a number of electro-magnetic devices, which operate in succession, each receiving device being controlled by a selected plurality of electro-magnetic devices, said electro-magnetic devices being unresponsive to the current of normal wave form, but being responsive to modified waves. We preferably employ relay mechanism included in the line circuit which is responsive to current of modified wave form and which directly governs the selection of said electro-magnetic devices, whereby a plurality of these electro-magnetic devices may, in turn, select the responsive devices. These responsive devices are desirably in the form of type-bar magnets, each of which serves to place the type-bar associated therewith in position to be operated. We prefer to employ alternating current upon the line, but we do not wish to be limited to such current.

We will describe our invention more fully by reference to the accompanying drawings, showing the preferred embodiment thereof, in which—

Figure 1 is a view of the transmitting end of the system, together with a portion of the line extending therefrom. Fig. 2 is a view of the receiving end of the system. Fig. 3 is a view illustrating diagrammatically waves of current impressed upon the line each time a selecting key is operated at the transmitting station.

The transmission line *a* terminates at the station A from which signals are being transmitted in an armature 1, that is subject to the influence of a polarized relay having operating windings 2, 3. The principle upon which the system operates is such that when the line *a* is in normal or idle condition, the armature 1 occupies that one of its alternative positions in which the grounded source of unidirectional current 4 is included in circuit with the said armature switch 1 and the line *a*. In this normal or idle condition, a grounded circuit is established for the line *a*, which may be traced from the grounded terminal of the battery 4, through the armature switch 1, the resistance 5, the right-hand half 6 of the differential relay 7, the winding 8 of a polarized relay (the elements just named being at the transmitting station A), the winding 9 of a polarized relay, the winding of relay 10, the winding 11 companion to the winding 9 and belonging to the same polarized relay therewith, the adjustable artificial resistances 12, 13, to ground (the elements latterly named being located at the receiving station B). A connection is observed extending from the middle of the winding of relay 10. This connection extends to apparatus similar to and in the same way as the connection shown extending from the middle of the winding of relay 7 in Fig. 1, this circuit arrangement being well known to those familiar with the art and being omitted in connection with relay 10 owing to the lack of space. At the transmitting station, there is shown a conductor in bridge of the grounded line *a*, that includes a resistance 14 and a switch 15, it being the design to have the switch 15 opened by a magnet 16 (the armature of the magnet, when attracted, being adapted to separate the contacts of the switch 15).

When the armature of magnet 16 is attracted, it also, by means of its electrical connections, serves to shunt the resistance 5 from the line, further to promote wave 5 form amplification or modification. The resistances 5 and 14 are so proportioned with respect to the line resistance and the battery 10 normally present upon the line, that a given minimum amount of current is constantly flowing over the line. A second ground connection at the transmitting station, includes the adjustable resistances 17, 18, that are conductively connected with ground, and which 15 are connected with ground through capacity 19, the branch conductor containing the resistances 17, 18 also including the left-hand winding of the differentially-wound magnet 7. At the receiving station, the resistances 20, 12, 13 are also conductively connected with ground, and are further connected with ground through capacity 20.

The line circuit thus far described is quite familiar to those skilled in the art, it being found present in commercial forms of quadruplex telegraphy, a part only of the apparatus being illustrated in connection with the line α , to enable our invention to be understood. We have shown in the drawings but one receiving station B and one 25 transmitting station A, together with sufficient of the apparatus in association with the line α to show how selective currents are transmitted between the transmitting and receiving stations. It will be apparent to 30 those skilled in the art, particularly after the invention is further explained, that there may be a transmitting and receiving station at each end of the same line α . We will not describe in further detail any of the equipment that enters peculiarly into the line 35 equipment, such being so well known to those skilled in the art.

In accordance with our invention, continuous current of one sign, and furnished, 40 for example, by the battery 4, is normally in circuit with the line α by way of the armature switch 1. By way of example, it may be assumed that the current furnished by the battery 4 thus normally present upon the line, is of positive sign, whenever character 45 selecting current is impressed upon the line. We prefer to impress current upon such line which has eight alternations; that is, we prefer in some way to replace the current due 50 solely to the battery 4, by current which will have a reverse or negative sign, to produce the first alternation, whereafter the current of positive sign is impressed upon the line to produce a second alternation, whereafter 55 current of negative sign is impressed upon the line to produce the third alternation, and so on until four alternations of negative sign, joined or in tandem arrangement with four alternations of positive current, have 60 occurred, whereupon the character selecting 65

current is abruptly removed from the line α , in order that the work of selection, as a result of the transmitted current, which has been accomplished, may not be defeated. It is theoretically possible to provide a peculiar 70 form of alternating current generator that may be temporarily associated with the line α , so as to give the required alternations, but from a practical viewpoint, such a generator does not give the most efficient service, and 75 we, therefore, employ relay mechanism that is adapted alternately to include the windings 2, 3 of the same polarized magnet that governs the armature switch 1, in circuit with undirectional current, so that the battery 4, furnishing positive current, may be taken off the line α and may be replaced by the battery 21, furnishing unidirectional current of negative sign, it being our preferred practice to use two batteries 4 and 21, furnishing currents of opposite sign and adapted, one to be substituted for the other, according to the operation of the switch 1, but we do not wish to be limited in all embodiments of our invention to the way in 80 which current from battery 4 normally flowing to the line α is replaced by suitable alternating current.

What has thus far been said with respect to the current impressed upon the line α is 85 graphically illustrated in Fig. 3, which shows a line of sinusoidal wave form terminating at its ends in straight lines 22, which serve to illustrate the normal presence of positive direct current upon the line 90 α . The first alternation which occurs when the battery 21 is substituted for the battery 4, is illustrated at 23 below the median line 24. The next alternation which occurs upon the substitution of the battery 4 for the battery 21 is illustrated above the median line 24 at 25, and so on, the additional curves 26, 27, 28 below the line 24 representing the current that is present due to the battery 21 and the additional curves 29, 30 and 31 above 100 the line 24 indicating the current that is due to the re-association of the battery 4 with the line. While in Fig. 3 we have shown the curves 23, 26, 27, 28 as being very slightly disjointed from the curves 22, 25, 29, 30, 31, due to the fact that the armature switch 1 breaks before making contact, yet we do not 105 wish to be limited to this very slightly disjointed relation of said curves. The current of the form illustrated in Fig. 3 is not 110 in itself adapted to constitute a character selecting current, it being necessary, in accordance with the preferred embodiment of our invention, to amplify or modify the amplitude of certain of the waves, that wave or those waves being amplified which will 115 perform the work that is to be done at the receiving station, as will appear. This modification of a wave or waves of the alternating current impressed upon the line α is de- 120 125 130

sirably effected by operating the magnet 16, so that it may open the switch 15 during the time that a particular selected wave or selected waves are present, so that such wave or waves may be modified or amplified owing to the removal of the shunt including the resistance 14, from across the main line a and the short circuiting of resistance 5.

Having now generally outlined the character of the operating current that is to be impressed upon the line a , and the method of controlling the nature of such current, we will now describe the apparatus at the transmitting station by which we prefer to cause alternating current to be impressed upon the line, and by which we prefer to cause selected waves to be amplified or otherwise modified. At the transmitting station, there are as many character keys 32, 33, 34, 35 as there are characters to be reproduced at the receiving station. Each character key includes a main contact spring 36 bearing the key button and three contacts 37, 38, 39, the elements 36, 37, 38, 39 of each character key being normally out of contact and being brought into electrical connection with each other when a key including the same is depressed. When any character key or character switch is depressed, a circuit is established by the contact 39 of such key (the contacts 39 of all of the keys having a common connection 40), which circuit may be traced from the grounded battery 41, through one coil 42 of a polarized relay, the contact 39 of the operated key, to the ground 43, the conductor leading to the ground 43 being connected with coils 44, 45, 46, 47, 48, 49, 50, 51 of polarized relays whose functions will hereinafter appear. The polarity of the battery 41 is such that when it is included in circuit with the coil 42, the armature 52 is shifted into engagement with its live contact, whereby the following results occur: Current from the grounded battery 41 passes to the armature switch 52, to the armature switch 53, the actuating coil 54, which pulls the armature switch 53 to the left, said armature switch 53 being followed by its normal contact sufficiently long to permit the coil 54 to perform its function, whereafter circuit through the coil 54 is broken, owing to the separation of the armature switch 53 from its normal contact, thence to the armature switch 55, thence to the actuating coil 56, which pulls the armature switch 55 to the left, said armature switch 55 being followed by its normal contact sufficiently long to permit the coil 56 to perform its function, whereafter circuit through the coil 56 is broken, owing to the separation of the armature switch 55 from its normal contact, this process of connection being repeated throughout the remaining armature switches 57, 59, 61, 63, 65, 67 and 68 energizing coils 58, 60, 62, 64, 66, 68 of po-

larized relays, the inter-relation of the armature switches 57, 59, etc., with the energizing coils 58, 60, etc., of polarized relays being similar to the inter-relation of the armature switches 53, 55 with the coils 54, 56, whereby the armature switches 53, 55, 57, etc., are successively operated respectively by their coils 54, 56 to cause the successive inclusion of said armature switches in serial relation with each other and with the battery 41. The alternate contact of the final armature switch 67 is grounded at 67¹, so that this armature switch 67 may cause the establishment of a circuit to enable the coil 69 to perform the functions to be stated. The coils 54, 58, 62, 66, when successively included in circuit momentarily for the purpose of moving their armature switches toward the left, are successively included in circuit with the polarized magnet coil 2. The coils 56, 60, 64, 68, when successively included in circuit momentarily for the purpose of moving their armature switches toward the left, are successively included in circuit with the polarized magnet coil 3, the grounded terminals of the coils 2 and 3 being complementary to the grounded terminal of the battery 41, so far as the circuits of the coils 54, 56, etc., are concerned. Thus before the first armature switch 53 is operated and after the armature switch 52 is operated, circuit for the coil 2 is closed to shift the armature switch 1 so as to impress negative battery 21 upon the line a to produce the wave form 23, whereafter circuit for this coil 2 is opened, owing to the movement of the armature switch 53 to the left. When the armature switch 53 engages its alternate contact, the coil 3 is in circuit, causing the movement of the armature switch 1 to its normal position, in which positive current from the battery 4 is impressed upon the line, thereby forming the wave 25. In similar manner, the armature switch 57 governs through the coil 2, the formation of the wave 26, the armature switch 29, through the coil 3, governs the formation of the wave 29, and so on throughout the series of eight wave forms, the final operation occurring through the agency of the armature switch 67, which places the armature switch 1 in its normal position, in which positive current from the battery 4 is impressed upon the line. The armature switch 67 is the last in the series of armature switches 53, 55, 57, 59, 61, 63, 65, 67 to be operated, and when operated, it is in connection with its ground 67¹ by way of its alternate contact, the alternate contact of the armature switch 67 being connected with the ground 67¹ by way of the relay 69, which constitutes a restoring relay. The armature switch of the relay 69 establishes, when actuated, a local metallic circuit, which includes the battery 69¹ and mates 70 to the coils 54, 56, 58, 60, 62, 64, 66, 68, whereby 132.

the armature switches previously moved to the left by said coils are moved to the right by the coils 70 to occupy their normal positions, the coils 70 being free to perform this function, as the coils 54, 56, etc., are then on open circuit. The coils 54, 56, etc., thus constitute actuating coils and the coils 70 thus constitute restoring coils. The metallic circuit which includes the coils 70 also includes the restoring coils 71 that are mates to the coils 44, 45, 46, 47, 48, 49, 50, 51, the purpose of all of which coils appearing later, the circuits established by the restoring relay 69 also including the coil 72 that is a mate to the coil 42, so that the armature switch 52 will be moved to the left to occupy its normal position.

Thus we have disclosed a system of magnets or relays that impresses an exact number of alternations of current upon the line *a* for purposes which will later appear, as a consequence of each character key or switch operation, when the apparatus at the receiving station shown in Fig. 2 is described. The coil 44 is shown in connection with the spring 36 of key 32, circuit being established through this coil 44 when the key 32 is depressed. The armature switch associated with the coil 44 is moved to the left by said coil when energized, whereupon circuit for the magnet 16 is closed, which circuit may be traced from the grounded terminal of said magnet, through the winding of the magnet, the armature switch associated with the coil 44, to the grounded battery 41, this circuit being maintained during the connection of the armature switch 53 with its normal contact, and, therefore, being maintained during the time that the coil 2 is energized, so that during the time negative current from the battery 21 is impressed upon the line, the shunt including the resistance 14 is broken by the separation of the contacts 15 and the resistance 5 is short-circuited, due to the operation of the magnet 16, whereby the wave 23 is modified or amplified for purposes which will appear when the apparatus at the receiving station is described. If key 33 were the key depressed, the coil 45 would be energized instead of the coil 44, so that the shunt 14 would be removed and the resistance 5 short-circuited during the time the wave 25 is being formed, thereby modifying or amplifying the wave 25. Some of the character keys, obviously, may close circuit through a number of such coils, as, for instance, the character key 32 is shown as being adapted not only to close circuit through the coil 44, but is also adapted to close circuit through coils 47 and 48 which have terminals in the springs 37, 38 of the key 32. Thus when the character key or switch 32 is operated, the wave 23 is not only modified or amplified, but waves 29 and 27 are also amplified

or modified; when character key or switch 33 is operated, the waves 25, 26 are amplified or modified, the contact spring 38 having no coil shown in connection therewith; when character key or switch 34 is operated, waves 26, 27 are modified or amplified; the character keys thus serving to cause the modification or amplification of particular waves or groups of waves to cause the presence of characteristic current upon the transmission line which will cause the operation of responsive devices at the receiving station suited thereto.

From what has been described, it will be seen that the coils 44, 45, 46, 47, 48, 49, 50, 51 are in co-operative relation with the armature switches 53, 55, 57, 59, 61, 63, 65, and 67 respectively, so that when any of the coils 44, 45, etc. are energized, the shunt 14 is broken and the resistance 5 is short-circuited to permit waves of current due to the engagement of the associate armature switches 53, etc. with their normal contacts, to be amplified or modified, the shunt 14 being immediately re-established and the short-circuit about the resistance 5 immediately removed when the wave modification has ceased. Thus each normal alternation occurs during the time an armature switch, as 53, is in engagement with its normal contact and is in circuit with the battery 41. It is during the period of this engagement of the normal contact of such armature switch with said armature switch that the wave of current is amplified or modified by the associate wave-modifying magnet, as 44.

The restoring circuit governed by the magnet 69 includes the coils 71, as has been stated, so that when the cycle of operations initiated by an operated character key has been concluded, the coils 71 are energized, to restore whatever armature switches associated therewith may have been moved, the relay 69, in one operation, thus serving to restore all of the apparatus at the transmitting station to its normal condition, as illustrated in Fig. 1.

Having now described what occurs at the transmitting station, and having shown in what manner alternating current of modified and unmodified wave form is impressed upon the line and is transmitted to the receiving station, we will now describe how this alternating current effects the operation of the receiving devices at the receiving station. The polarized relay 911 at the receiving station has an armature switch 72, which is normally maintained in engagement with a contact spring 73 through the agency of the coils 9 and 11, which are normally in circuit with the battery 4, the polarity of the current from the battery 4 being such that the coils 9 and 11 keep the armature switch 72 normally in the position illustrated. When the current impressed

upon the line *a* is first reversed, the armature switch 72 is shifted into engagement with its alternate grounded contact, whereupon circuit is established which may be traced from said alternate grounded contact, through the armature switch 72, to the armature switch 73¹, the normal contact of the armature switch 73¹, the operating coil 74 of a polarized relay, thence to grounded battery 75, the polarity of the battery 75 being such that the coil 74 is energized to move the armature switch 73¹ from its normal contact into engagement with its alternate contact. The armature switch 73¹ will engage its alternate contact after it has left its normal contact, the normal contact following the armature switch through a part of the movement of the armature switch, whereby the armature switch 76 next in succession will be connected with the armature switch 73¹ and with the armature switch 72, so that the current in its next alternation will find access to the coil 77 of the second polarized electromagnet, and inasmuch as the armature switch 76, similarly to the armature switch 73¹, is followed by its normal contact through a part of its movement, circuit for the coil 77 is maintained sufficiently long to permit the armature switch 76 to be shifted to its position where it engages its alternate contact, whereby the armature switch 76 is brought into connection with the third armature switch 78. The energizing circuit for the coil 77, however, is different from the energizing circuit for the coil 74, inasmuch as the armature switch 72 alternately forming parts of the two circuits, is on the second alternation of the current (during each time the battery 4 is connected with the line) brought into connection with the grounded battery 79 by way of the spring 73, rather than into engagement with its alternate grounded contact, current from the grounded battery 79 finding path through the elements 72-73 to the armature switch 73¹, the armature switch 76, then connected with the armature switch 73¹, through the coil 77 during the time its terminal is in connection with the armature switch 76, to the ground 80. When the armature switch 72 again engages its alternate contact, the coil 81 is included in circuit with the battery 75, at the next alternation the coil 82 is connected in circuit with the battery 79, at the next alternation the coil 83 is connected in circuit with the battery 75, at the next alternation the coil 84 is connected in circuit with the battery 79, at the next alternation the coil 85 is connected in circuit with the battery 75, and at the next alternation the coil 86 is connected in circuit with the battery 79. The coils 81 to 86, inclusive, form parts of polarized relays having armature switches similar to the armature switches of the po-

larized relays of which coils 74-77 form parts. The polarized relays including the coils 74-77, 81 to 86, inclusive, are thus always energized in succession independently of any wave modification, each relay of the series 70 being always operated, inasmuch as the operation of each relay depends upon a particular wave of the current. Thus when the battery 21 is first placed upon the line *a* to form a negative wave, the coil 74 is thereupon energized in consequence, in the manner which has been set forth; when the battery 4 is again placed upon the line *a*, the coil 77 is operated in consequence; when the battery 21 is again placed upon the line, the coil 81 is operated in consequence; when the battery 4 is again placed upon the line, the coil 82 is operated in consequence; when the battery 21 is again placed upon the line, the coil 83 is energized in consequence; when the battery 4 is again placed upon the line, the coil 84 is operated in consequence; when battery 21 is again placed upon the line, the coil 85 is operated in consequence; and when the battery 4 has been restored to its normal connection with the line, coil 86 is energized. In other words, the formation of the first wave is accompanied by the energization of coil 74; the formation of the second wave is accompanied by the energization of coil 77; the formation of the third wave is accompanied by the energization of coil 81, and so on, this being the case irrespective of the forms of the waves.

When the coil 86 has attracted the armature switch associated therewith, such armature switch, upon engaging its alternate contact, causes the establishment of a circuit which may be traced from the ground 87, through the relays 88-89 in series, to the terminal of the relay 86, constituting the alternate contact for the armature switch associated with the coil 86, through the armature switches now in serial relation with each other, as a consequence of their movements to the right, as has been described, the armature switch 72, the contact 73, now normally engaging the armature switch 72, to the grounded battery 79. The results occasioned by the energization of the relay 88 will be later explained. The relay 89, when thus energized, closes a local circuit which may be traced from the grounded battery 79, through the armature switch of the relay 89, the coils 90 companion to the coils 74-77 and 81 to 86, inclusive, to ground at 91, whereby the armature switches belonging to the coils mentioned are shifted to the left to occupy their normal positions, whereupon the polarized relays containing said coils and armature switches are restored to their normal positions, indicated in Fig. 2.

A single electromagnet common to the receiving apparatus, is included in circuit, that may be traced from the ground 93, to the

normal contact of the armature switch 94, to the grounded battery 95. The electro-magnet or relay 92 has eight armature switches adapted to close eight distinct circuits 96, 97, 98, 99, 100, 101, 102 and 103, which are provided for purposes hereinafter to be mentioned. The circuit 96 includes the uppermost armature switch of the relay 92 and is established, when the relay or magnet 92 is energized, during the connection of the armature switch 73¹ with its normal contact, when such armature switch 73¹ is in circuit with the grounded alternate contact of the armature switch 72. It is, therefore, apparent that if circuit 96 is to be established, it must be established during the presence of the first alternation occasioned at the first time the battery 21 is substituted for the battery 4. The magnet 10, in serial relation with the line *a* and subject to the wave form current, is so constructed that it will not be sufficiently energized when the wave form current has its waves unmodified; but as soon as said magnet 10 is subjected to an amplified wave of current, it will attract its armature switch 94, and inasmuch as the wave modification is limited to the period during which the wave undergoing modification is being formed, it is apparent that the magnet 10 can only be sufficiently energized to attract its armature switch during the presence of a given wave upon the line, provided such wave is amplified. Therefore, the circuit 96 is established during the presence of the first wave of current upon the line, provided such wave is amplified, and not otherwise. The circuit 97 includes the next armature switch from the top of the magnet 92, and is established if the magnet 92 is energized; it being understood that if the magnet 92 is to be energized, in order that this second armature switch from the top may be actuated to close circuit 97, such energization must occur during the formation of the second wave, and that such second wave must be amplified, in order to sufficiently energize the magnet 10 to close its armature switch 94, it being understood that each time the armature switch 94 is closed, the grounded battery 95 is included in closed circuit with the magnet 92. Thus when a wave of current of normal form is being impressed upon the line, the magnet 92 does not respond, and, therefore, the receiving apparatus beyond the magnet 92 is not influenced, although the normal waves and the amplified waves each serve to effect the energization of the coils 74 77 81 to 86, inclusive, as has been set forth. Similarly, the circuit 98 is closed when the third wave is modified; circuit 99 is closed when the fourth wave is amplified; circuit 100 is closed when the fifth wave is amplified; circuit 101 is closed when the sixth wave is amplified; circuit 102 is closed when the seventh

wave is amplified; and circuit 103 is closed when the eighth wave is amplified.

Each of the circuits 96 to 103, inclusive, includes responsive apparatus that governs the reproduction of the signals or characters 70 at the receiving station that correspond to the actuated character switches or keys 32, 33, etc., at the transmitting station. The circuits 96 to 103, inclusive, govern the type-bar magnets hereinafter to be numerically 75 designated, and each of which serves, when energized, to attract a catch, such as is illustrated at 104, each type-bar magnet having such a catch 104 individual thereto, said catches being operable independently of each 80 other. A printing magnet 105, whose control will be later set forth, is associated with the catch 104. The armature of the printing magnet, when energized, engages an attracted catch 104 and escapes the remaining and 85 unattracted catches, whereby the type-bar 106 is operated to cause the impression of the type associated with the type-bar, upon the record sheet 107.

The system of our invention has thus far 90 been sufficiently described to have it generally understood that when the character keys at the transmitting station are depressed, certain type-bar magnets, or equivalent devices, are thereupon selected to adjust the 95 type-bar structures to enable such type-bar structures to be operated individually, to print the record upon the sheet 107.

While we prefer to use typewriter structures as recording devices, we do not wish 100 to be limited to such an instrument in all embodiments of our invention. Lack of space prevents us from showing all of the type-bar magnets, constituting the preferred form of receiving devices, that desirably enter into the system of our invention. We have shown three groups of type-bar magnets, five magnets to a group. It is, of course, understood that the number of magnets per group may be, and desirably is, increased. One group of type-bar magnets 108 109 110 111 and 112; another group of type-bar magnets includes the magnets 113 114 115 116 and 117; the third group of type-bar magnets 118 to 122, inclusive, are selected and energized to attract the catches 104 individually associated therewith. Circuit for the type-bar magnet 118 includes the uppermost armature switch of the magnet 123, the uppermost armature switch of the magnet 124, the grounded contact of the latter armature switch, a conductor 125 leading from the type-bar magnet of the group including the type-bar magnet being selected, a corresponding normal contact of armature switch 126, the normal contact of 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 armature switch 127 (these two armature switches now occupying their normal positions, as illustrated), the relay or magnet 128, which governs the printing magnet, as 5 will appear, and the grounded battery 79. The magnets 123 and 124 must, therefore, be energized in order that type-bar magnet 118 may be selected, and inasmuch as these magnets 123 124 are respectively included in 10 circuits 98 and 103, the particular armature switches of magnet 92 included in such circuits 98 and 103, must be closed, in order to close the circuits 98 and 103. The magnet 92, therefore, must be energized in the 15 manner which has been outlined during the third and eighth wave of current impressed upon the main line *a*, and inasmuch as those armature switches of the magnets 123 and 124 that are included in the circuit of type-bar magnet 118 are in serial relation, it is 20 necessary to hold the magnets 123 and 124 in their energized conditions, it being apparent that the armature switches included in the initial energizing circuits of the magnets 123 and 124 are immediately opened 25 upon the cessation of the amplified current waves that caused the energization of the magnet 92 indirectly, all as has appeared. We desirably provide locking circuits for 30 such magnets as 123 and 124, which locking circuits include the battery 129, which is common thereto. The locking circuit for magnet 123 includes the two lowermost armature switches of the magnet 123, and may 35 be traced from the grounded battery 129, through the armature switch belonging to magnet 130, to the lowermost armature switch of magnet 123, the winding of magnet 123, to the next to the lowermost armature switch of magnet 123, thence to ground 40 at 131, said magnet 123 having been energized in the manner that has been stated. The locking circuit for magnet 124 may be traced from the grounded battery 129, 45 through the armature switch of magnet 130, the next to the lowermost armature switch of magnet 124, the contact for said armature switch, the winding of magnet 124, to the lowermost armature switch of magnet 50 124, to the grounded armature switch of relay 131. When type bar magnet 119 is to be selected, the magnets 123 and 132 must be energized, as the armature switches of these magnets jointly determine the circuit 55 of the type-bar magnet 119. The magnet 123 is energized owing to the closure of circuit 98 therethrough when the third wave upon the main line is amplified, as has been described, and circuit of magnet 132 is 60 closed when its circuit 102 is established upon the amplification of the seventh wave. The magnet being selected includes in its circuit another conductor 125 similar to the previously described conductor 125. It will be unnecessary to describe the locking cir-

cuit of magnet 132, which is similar to the locking circuit of magnet 124.

When it is desired to select type-bar magnet 120, the magnets 123 and 133 are included in their energizing circuits, magnet 133 being included in circuit 101, which is established when the sixth wave is amplified. In the selection of this third type-bar magnet, another conductor 125 is employed. If it is desired to select type-bar magnet 121, 75 magnets 123 and 134 have their energizing circuits closed, the magnet 134 being included in circuit 100, which is established when the fifth wave is amplified. If it is desired to select type-bar magnet 122, magnets 123 and 135 are energized, magnet 135 being included in circuit 99, which is established when the fourth wave is amplified. Thus, in selecting type-bar magnets in the group composed of magnets 118 to 122, inclusive, magnet 123 is energized each time, which is upon the amplification of the third wave. During the state of energization of magnet 123, one of the other magnets 124, 80 132, 133, 134 and 135 is energized, one for each of the type-bar magnets to be selected, the magnet 124 being energized for selecting magnet 118; the magnet 132 being energized for selecting magnet 119; the magnet 133 being energized for selecting magnet 120; the magnet 134 being energized for selecting magnet 121; and the magnet 135 being energized for selecting the magnet 122. 85 Each time a type-bar magnet has been thus selected and energized, it operates a catch, such as catch 104, whereafter the printing magnet 105 is energized, as will be described, in order to occasion the application of the type carried by the type-bar, to the paper 107. Obviously, the number of type-bar 90 magnets in each group may be increased or diminished, as desired, we having selected five type-bar magnets per group in order to illustrate our invention, space not well permitting of the illustration of more type-bar magnets. The group of type-bar magnets that have thus been particularly described, depend upon the connection of their conductors 125 with the armature switches 126 95 102. When the type-bar magnets of any of the other two groups are to be selected, the conductors 125 should be disconnected, which is accomplished by shifting one or the other of the two armature switches 126 110 127 that are normally in serial relation with each other, and a conductor, generally similar in function to the conductors 125, should be brought into relation with that group of type-bar magnets from among 115 which certain type-bar magnets are to be selected. If type-bar magnets of the group containing magnets 113 114 115 116 and 117 are to be selected, the conductors 136 leading from the type-bar magnets of this second group, are to be brought into circuit 120 130

relation with the magnet 128, this result being accomplished by shifting the armature switch 126 to the left, armature switch 127 being allowed to remain in its normal position. The armature switch 126 is shifted toward the left by amplifying the first wave of current that is impressed upon the line; that is, this armature switch 126 is shifted to the left when the battery 21 is first substituted for the battery 4 upon the operation of a suitable character key that will occasion, in the manner which has been described in connection with the transmitting station, the amplification of the first wave impressed upon the line. When the first wave is amplified, the magnet 10 is subject to sufficiently increased current to occasion its energization, whereupon circuit may be traced from the grounded battery 95, through the armature switch 94, through the magnet 92, to its ground, whereby circuit 96 is established to occasion the energization of the coil 137 of the polarized relay having the armature switch 126, this coil 137 drawing the armature 126 to the left, whereby the conductors 125 are removed from circuit relation with the first set of type-bar magnets 118 to 122, inclusive, and the conductors 136 are placed in proper circuit relation with the type-bar magnets of the second group that is being described, and numbered 113 to 117, inclusive.

The conductors 136, as a consequence of the movement of the armature 126, are brought into circuit relation with the magnet 128, which is like the circuit relation that the conductors 125 previously had with said magnet 128, as a consequence of which the type-bar magnets of the second group may readily be selected, the character keys at the transmitting station which cause this selection each serving to occasion three wave amplifications, instead of two, the first wave amplification always occurring in connection with the first wave impressed upon the transmission line and the two additional wave amplifications occurring according to the type-bar magnet of the second group which is to be selected, energizing circuit through the magnet 123 always being closed when any of the type-bar magnets of the second group are to be selected (the energizing circuit of the magnet 123, in fact, always being closed when any type-bar magnet is being selected, as the system is illustrated), while, in addition to the closure of the circuit for this magnet 123, the energizing circuits of magnet 124, 132, 133, 134 and 135 are closed when the type-bar magnets 113, 114, 115, 116 and 117 are to be selected, magnet 124 being energized when the type-bar magnet 113 is to be selected; magnet 132 being energized when the type-bar magnet 114 is to be selected; magnet 133 being energized when the type-bar magnet 115 is to be

selected; magnet 134 being energized when the type-bar magnet 116 is to be selected; and magnet 135 being energized when the type-bar magnet 117 is to be selected. While, as shown, the magnet 123 is energized each time a type-bar magnet is to be selected, such is the case only in view of the system as illustrated, lack of space preventing us from showing that it is not necessary to have magnet 123 energized each time a type-bar magnet is being selected. With our system, two magnets, similar to the magnets 124, 135, 134, 133 and 132, may be selected, provided they are in suitable circuit relation with the type-bar magnets that have been shown, conductors 135¹ being associated with the armature switches of magnet 135, conductors 134¹ being associated with the armature switches of magnet 134, conductors 133¹ being associated with the armature switches 133, and conductor 132¹ being associated with the armature switch 132, each one of these conductors being provided for connection with three type-bar magnets distributed among the three groups.

If the type-bar magnets of the group including type-bar magnets numbered 108 to 112, inclusive, are to be selected, the conductors 138 extending from the type-bar magnets of this third group are placed in proper circuit relation with the magnet 128, which result is accomplished by the operation of a character key at the transmitting station which will occasion the amplification of the second wave impressed upon the line, in order that the switch 127 may be moved to the right, for the purpose of connecting the conductors 138 with the magnet 128. When the second wave is amplified, the first wave is not amplified, as the armature switch 126 should remain in its normal condition. When this second wave is amplified, magnet 92 is again energized and circuit 97 is established, which circuit includes the actuating coil 139 belonging to a polarized relay that includes the armature switch 127, to bring said armature switch into electrical connection with the conductors 138, for the purpose specified. When the type-bar magnets of the third group of five are to be selected, the magnet 123 again is energized (as the system is shown) each time one of such type-bar magnets is to be selected, and magnet 124 is energized when type-bar magnet 108 is to be selected, magnet 132 is energized when the type-bar magnet 114 is to be selected, magnet 133 is energized when type-bar magnet 115 is to be selected, magnet 134 is energized when type-bar magnet 116 is to be selected, and magnet 135 is energized when type-bar magnet 117 is to be selected. We have thus provided three groups of type-bar magnets, the magnets of one of which being selectable when two

waves beyond the second wave impressed upon the line are amplified. When the type-bar magnets of the other two groups are to be selected, two selected waves beyond the second wave are to be amplified, and in addition thereto, the first or second wave is to be amplified, according to the group of type-bar magnets from which selection is to be made. After a type-bar magnet has been selected, and the type-bar catch 104 has been thereby attracted, the printing magnet 105 has circuit closed therethrough, which closure is effected by the closure of the armature switch belonging to magnet 128, this magnet 128 including in its circuit, battery 79, the selected type-bar magnet, and the two armature switches among the relays 128, 124, 132, 133, 134 and 135 that are employed to establish the circuit for the selected type-bar magnet; the magnet 105 operating sluggishly as compared with the operation of the type-bar magnets, in order to give said type-bar magnets opportunity to attract their catches 104 before the armature of magnet 105 is attracted. The circuit that is established by the armature switch of relay 128 through the printing magnet 105, may be traced from the grounded terminal of magnet 105, through the armature switch of magnet 128, and also through the battery 79.

After the printing magnet 105 has operated the catch 104 of the selected type-bar magnet, to cause the type upon the type-bar to make the impression, it operates an armature switch 140, whereby a circuit is established which may be traced from the ground 87, through the winding of magnet 88, the armature switch 140, to the grounded battery 79, whereby the magnet 88 is energized to establish circuit which may be traced from grounded battery 79, through the armature switch of magnet 88, through the windings of magnet 131, 130 in series, through the restoring coils 141, 141 belonging to the relays including the actuating coils 137 139, to ground, whereby said restoring coils 141 are energized, to attract one or the other of the armature switches 126, 127 to its normal position, if such armature switch has been shifted from its normal position (said restoring coils 141 having no operative effect upon the armature switches 126, 127 when such switches are not shifted from the normal positions), so that the conductors 136, 138 are removed from operative circuit relation with the groups of type-bar magnets associated therewith to enable those character keys at the transmitting station which are adapted to amplify only those waves beyond the first and second waves, to select type-bar magnets from among the first group, numbered 118 to 122, inclusive, the conductors 125 having been brought into their normal circuit relation with the mag-

net 128 as a consequence of the energizing circuit established through the restoring coils 141. The relays 130, 131 having been energized as a consequence of their inclusion in the same circuit with the restoring coils 141, cause the attraction of their armature switches, and thereby the breaking of the locking circuits for the two actuated magnets among the group including magnets 124, 132, 133, 134, 135 and 123.

It will be seen that upon the closure of the contacts 140, the printing magnet is excluded from circuit, thereby releasing the catch 104, which is permitted to be restored to its normal position owing to the fact that the type-bar relay that previously actuated it has its circuit opened as a consequence of the opening of the locking circuits supplied for the magnets 123, 124, 132, 133, 134 and 135. Thus the magnet 88 sets into operation a number of instrumentalities that cause the restoration to normal of all of the apparatus at the receiving station, excepting those polarized relays including the coils 74, 77, etc. which were previously restored, in the manner previously described, by the relay 89.

We provide a magnet 142 having an armature switch provided with contacts that form additional circuit terminals for the restoring circuits including the coils 90 and 130 and 131, the armature switch of magnet 142 being attracted when the battery 4 is normally upon the line, the magnet 142 being a sluggishly operating magnet, so that during the impression of current waves upon the line it will not have opportunity to be energized to attract its armature switch. If there should be any line interruption, or other cause preventing the proper impression of the eight waves upon the line, the magnet 142 will, when the battery 4 has its normal connection with the line, become energized, thereby to close the restoring circuits mentioned, so that if there has been but partial operation at the receiving station of the apparatus there located, the partially operated apparatus will be restored to normal, so that when the next character is to be recorded at the receiving station, the apparatus at the receiving station will be in condition to permit of such recording.

While we have herein shown and particularly described the preferred embodiment of our invention, we do not wish to be limited to the precise apparatus and circuit arrangements shown, as changes may readily be made in the preferred embodiment of our invention without departing from the spirit thereof, but,

Having thus described our invention, we claim as new and desire to secure by Letters Patent the following:

1. A system of transmitting intelligence including a transmission line extending from a transmitting station to a receiving

station, a series of relays operating in succession and each serving to cause the impression of a current wave upon the line and together the impression of waves in fixed order, means for effecting modification of normal wave formation and restricted to operate within the period of formation of the wave undergoing modification, and electro-magnetic responsive apparatus at the receiving station.

2. A system of transmitting intelligence including a transmission line extending from a transmitting station to a receiving station, a series of relays operating in succession and each serving to cause the impression of a current wave upon the line and together the impression of waves in fixed order, means for effecting modification of the normal current waves, means for selecting waves to be modified and timing the operation of the aforesaid means to occur within, and be limited to, the period of formation of the wave undergoing modification, and electro-magnetic responsive apparatus at the receiving station.

3. A system of transmitting intelligence including a transmission line extending from a transmitting station to a receiving station, a series of relays operating in succession and each serving to cause the impression of a current wave upon the line and together the impression of waves in fixed order, means for effecting modification of normal wave formation, means for causing the wave-modifying means to operate substantially throughout the period occupied in the formation of the wave to be modified and serving to restrict the action of the modifying means to such period, and electro-magnetic responsive apparatus at the receiving station.

4. A system of transmitting intelligence including a transmission line extending from a transmitting station to a receiving station, a series of relays operating in succession and each serving to cause the impression of a current wave upon the line and together the impression of waves in fixed order, means for modifying the normal current waves, means for selecting the waves to be modified and causing the modification of each wave under modification to occur substantially throughout, and be limited to, the period of formation of such wave, and electro-magnetic responsive apparatus at the receiving station.

5. A system of transmitting intelligence including a transmission line extending from a transmitting station to a receiving station, a series of relays operating in succession and each serving to cause the impression of a current wave upon the line, relay mechanism for effecting individual wave modification and restricted to operate within the period of formation of the wave un-

dergoing modification, and electro-magnetic responsive apparatus at the receiving station.

6. A system of transmitting intelligence including a transmission line extending from a transmitting station to a receiving station, means for impressing wave form current thereupon, means for effecting modification of the current waves, a plurality of successively operating relays, each adapted to bring the means for effecting wave modification into action, means for selecting the wave-modifying relays to be operated, thereby to occasion modification of selected waves, and electro-magnetic responsive apparatus at the receiving station.

7. A system of transmitting intelligence including a transmission line extending from a transmitting station to a receiving station, a series of relays operating in succession and each serving to cause the impression of a current wave upon the line, means for effecting modification of the current waves, a plurality of successively operating relays, each adapted to bring the means for effecting wave modification into action, means for selecting the wave-modifying relays to be operated, thereby to occasion modification of selected waves, and electro-magnetic responsive apparatus at the receiving station.

8. A system of transmitting intelligence including a transmission line extending from a transmitting station to a receiving station, means for impressing wave form current thereupon, means for effecting modification of the current waves, a plurality of successively operating relays, each adapted to bring the means for effecting wave modification into action, means for selecting the wave-modifying relays to be operated, thereby to occasion modification of selected waves, means for timing the operation of the selected wave-modifying relays to cause the wave modification of each wave to be modified to last throughout, and be limited to, the period of formation of such wave, and electro-magnetic responsive apparatus at the receiving station.

9. A system of transmitting intelligence including a transmission line extending from a transmitting station to a receiving station, a series of relays operating in succession and each serving to cause the impression of a current wave upon the line, means for effecting modification of the current waves, a plurality of successively operating relays, each adapted to bring the means for effecting wave modification into action, means for selecting the wave-modifying relays to be operated, thereby to occasion modification of selected waves, means for timing the operation of the selected wave-modifying relays to cause the wave modification of each wave to be modified to

last throughout, and be limited to, the period of formation of such wave, and electro-magnetic responsive apparatus at the receiving station.

5 10. A system of transmitting intelligence including a transmission line extending from a transmitting station to a receiving station, a series of relays operating in succession and jointly serving to cause the impression of alternating current upon the line, means for effecting individual wave modification and restricted to operate within the period of formation of the wave undergoing modification, and electro-magnetic responsive apparatus at the receiving station.

10 11. A system of transmitting intelligence including a transmission line extending from a transmitting station to a receiving station, a series of relays operating in succession and jointly serving to cause the impression of alternating current upon the line, means for effecting individual wave modification and restricted to operate within the period of formation of the wave undergoing modification, and electro-magnetic responsive apparatus at the receiving station.

15 12. A system of transmitting intelligence including a transmission line extending from a transmitting station to a receiving station, a series of relays operating in succession and jointly serving to cause the impression of alternating current upon the line, means for effecting individual wave modification, means for causing the wave-modifying means to operate substantially throughout the period occupied in the formation of the wave to be modified and serving to restrict the action of the modifying means to such period, and electro-magnetic responsive apparatus at the receiving station.

45 13. A system of transmitting intelligence including a transmission line extending from a transmitting station to a receiving station, a series of relays operating in succession and jointly serving to cause the impression of alternating current upon the line, means for modifying the current waves, means for selecting the waves to be modified and causing the modification of each wave under modification to occur substantially throughout, and be limited to, the period of formation of such wave, and electro-magnetic responsive apparatus at the receiving station.

60 14. A system of transmitting intelligence including a transmission line extending from a transmitting station to a receiving station, means for impressing alternating current thereupon, relay mechanism for effecting individual wave modification and

restricted to operate within the period of formation of the wave undergoing modification, and electro-magnetic responsive apparatus at the receiving station.

65 15. A system of transmitting intelligence including a transmission line extending from a transmitting station to a receiving station, a series of relays operating in succession and jointly serving to cause the impression of alternating current upon the line, relay mechanism for effecting individual wave modification and restricted to operate within the period of formation of the wave undergoing modification, and electro-magnetic responsive apparatus at the receiving station.

70 16. A system of transmitting intelligence including a transmission line extending from a transmitting station to a receiving station, means for impressing alternating current thereupon, means for effecting modification of the current waves, a plurality of successively operating relays, each adapted to bring the means for effecting wave modification into action, means for selecting the wave-modifying relays to be operated, thereby to occasion modification of selected waves, and electro-magnetic responsive apparatus at the receiving station.

75 17. A system of transmitting intelligence including a transmission line extending from a transmitting station to a receiving station, a series of relays operating in succession and jointly serving to cause the impression of alternating current upon the line, means for effecting modification of the current waves, a plurality of successively operating relays, each adapted to bring the means for effecting wave modification into action, means for selecting the wave-modifying relays to be operated, thereby to occasion modification of selected waves, and electro-magnetic responsive apparatus at the receiving station.

80 18. A system of transmitting intelligence including a transmission line extending from a transmitting station to a receiving station, means for impressing alternating current thereupon, means for effecting modification of the current waves, a plurality of successively operating relays, each adapted to bring the means for effecting wave modification into action, means for selecting the wave-modifying relays to be operated, thereby to occasion modification of selected waves, means for timing the operation of the selected wave-modifying relays to cause the wave modification of each wave to be modified to last throughout, and be limited to, the period of formation of such wave, and electro-magnetic responsive apparatus at the receiving station.

85 19. A system of transmitting intelligence including a transmission line extending from a transmitting station to a receiving station,

- a series of relays operating in succession and jointly serving to cause the impression of alternating current upon the line, means for effecting modification of the current waves, 5 a plurality of successively operating relays, each adapted to bring the means for effecting wave modification into action, means for selecting the wave-modifying relays to be operated, thereby to occasion modification of 10 selected waves, means for timing the operation of the selected wave-modifying relays to cause the wave modification of each wave to be modified to last throughout, and be limited to, the period of formation of such 15 wave, and electro-magnetic responsive apparatus at the receiving station.
20. A system of transmitting intelligence including a transmission line extending from a transmitting station to a receiving station, 20 a plurality of relays operating in succession and each serving to cause the impression of a wave of current upon the line, the relays operating together to cause the wave forms impressed upon the line to alternate, whereby 25 by the current impressed upon the line constitutes an alternating current, and electro-magnetic responsive apparatus at the receiving station.
21. A system of transmitting intelligence 30 including a transmission line extending from a transmitting station to a receiving station, a plurality of relays operating in succession and each serving to cause the impression of a wave of current upon the line, the relays 35 operating together to cause the wave forms impressed upon the line to alternate, whereby the current impressed upon the line constitutes an alternating current, means for effecting individual wave modification and 40 restricted to operate within the period of formation of the wave undergoing modification, and electro-magnetic responsive apparatus at the receiving station.
22. A system of transmitting intelligence 45 including a transmission line extending from a transmitting station to a receiving station, a plurality of relays operating in succession and each serving to cause the impression of a wave of current upon the line, the relays 50 operating together to cause the wave forms impressed upon the line to alternate, whereby the current impressed upon the line constitutes an alternating current, means for effecting wave modification, and electro- 55 magnetic responsive apparatus at the receiving station.
28. A system of transmitting intelligence including a transmission line extending from a transmitting station to a receiving station, 60 a plurality of relays operating in succession and each serving to cause the impression of a wave of current upon the line, the relays operating together to cause the wave forms impressed upon the line to alternate, whereby 65 by the current impressed upon the line con-
- stitutes an alternating current, means for effecting wave modification, means for selecting waves to be modified, and electro-magnetic responsive apparatus at the receiving station. 70
24. A system of transmitting intelligence including a transmission line extending from a transmitting station to a receiving station, a plurality of relays operating in succession and each serving to cause the impression of a wave of current upon the line, the relays operating together to cause the wave forms impressed upon the line to alternate, whereby the current impressed upon the line constitutes an alternating current, means for effecting individual wave modification and restricted to operate within the period of formation of the wave undergoing modification, means for selecting waves to be modified, an electro-magnetic responsive apparatus at the receiving station. 75 80
25. A system of transmitting intelligence including a transmission line extending from a transmitting station to a receiving station, means for impressing wave form current upon the line at the transmitting station, a plurality of receiving devices at the receiving station, a number of electro-magnetic devices at the receiving station operable in succession, each receiving device 90 being controllable by a selected plurality of electro-magnetic devices, a line relay unresponsive to the normal current waves and responsive to current of modified wave form and operable upon wave modification, and a 95 plurality of additional relays, one corresponding to each electro-magnetic device and operable by the line current whether the waves are modified or unmodified, each of the latter relays being responsive to a particular wave of the series of waves of line current, and therefore being operable in succession, each of said additional relays being adapted to coöperate in turn with the aforesaid line relay when said line relay is operated to effect the operation of the electro-magnetic device associated therewith. 100 105 110
26. A system of transmitting intelligence including a transmission line extending from a transmitting station to a receiving station, means for impressing wave form current upon the line at the transmitting station, a plurality of receiving devices at the receiving station, a number of electro-magnetic devices at the receiving station operable in succession, each receiving device 115 being controllable by a selected plurality of electro-magnetic devices, a line relay unresponsive to the normal current waves and responsive to current of modified wave form 120 and operable upon wave modification, a plurality of additional relays, one corresponding to each electro-magnetic device and operable by the line current whether the waves are modified or unmodified, each of the lat- 125 130

5 ter relays being responsive to a particular wave of the series of waves of line current, and therefore being operable in succession, each of said additional relays being adapted to coöperate in turn with the aforesaid line relay when said line relay is operated to effect the operation of the electro-magnetic device associated therewith, locking circuits established by the operated electro-magnetic 10 devices through the electro-magnets thereof, and means for opening the closed locking circuits after the selection of an electro-magnetic responsive device.

15 27. A system of transmitting intelligence including a transmission line extending from a transmitting station to a receiving station, means for impressing wave form current upon the line at the transmitting station, a plurality of receiving devices at 20 the receiving station, a number of electro-magnetic devices at the receiving station operable in succession, each receiving device being controllable by a selected plurality of electro-magnetic devices, a line relay unresponsive to the normal current waves and 25 responsive to current of modified wave form and operable upon wave modification, a plurality of additional relays, one corresponding to each electro-magnetic device and 30 erable by the line current whether the waves are modified or unmodified, each of the latter relays being responsive to a particular wave of the series of waves of line current, and therefore being operable in succession, 35 each of said additional relays being adapted to coöperate in turn with the aforesaid line relay when said line relay is operated to effect the operation of the electro-magnetic device associated therewith and to restore 40 the successively operating relays, locking circuits established by the operated electro-magnetic devices through the electro-magnets thereof, and means for opening the closed locking circuits after the selection of 45 an electro-magnetic responsive device.

28. A system of transmitting intelligence including a transmission line extending from a transmitting station to a receiving station, means for impressing wave form current upon the line at the transmitting station, a plurality of receiving devices at 50 the receiving station, a number of electro-magnetic devices at the receiving station operable in succession, each receiving device 55 being controllable by a selected plurality of electro-magnetic devices, a line relay unresponsive to the normal current waves and responsive to current of modified wave form and operable upon wave modification, and 60 a plurality of additional relays, one corresponding to each electro-magnetic device and operable by the line current whether the waves are modified or unmodified, each of 65 the latter relays being responsive to a particular wave of the series of waves of line

70 current, and therefore being operable in succession, each of said additional relays being adapted to coöperate in turn with the aforesaid line relay when said line relay is operated to effect the operation of the electro-magnetic device associated therewith, the additional relays having armature switches successively actuated by successive current waves, said armature switches being in serial relation with each other, each armature switch being normally separated from the next armature switch and being connected therewith upon actuation, the magnets of 75 said electro-magnetic devices being normally in circuit relation with the armature switch of the relay associated therewith, said line relay serving to complete the energizing circuit for a selected electro-magnetic device.

80 29. A system of transmitting intelligence including a transmission line extending from a transmitting station to a receiving station, means for impressing wave form current upon the line at the transmitting station, a plurality of receiving devices at 85 the receiving station, a number of electro-magnetic devices at the receiving station operable in succession, each receiving device being controllable by a selected plurality of electro-magnetic devices, a line relay unresponsive to the normal current waves and 90 responsive to current of modified wave form and operable upon wave modification, a plurality of additional relays, one corresponding to each electro-magnetic device and 95 operable by the line current whether the waves are modified or unmodified, each of the latter relays being responsive to a particular wave of the series of waves of line current, and therefore being operable in succession, each of said additional relays being adapted to coöperate in turn with the aforesaid line relay when said line relay is 100 operated to effect the operation of the electro-magnetic device associated therewith and to restore the successively operating relays, the additional relays having armature switches successively actuated by successive current waves, said armature switches being in serial relation with each other, each armature switch being normally separated from the next armature switch and being connected therewith upon actuation, the magnets of 105 said electro-magnetic devices being normally in circuit relation with the armature switch of the relay associated therewith, said line relay serving to complete the energizing circuit for a selected electro-magnetic device, locking circuits established by the operated electro-magnetic devices through the electro-magnets thereof, and means for opening the closed locking circuits after the selection of an electro-magnetic responsive device.

110 30. A system of transmitting intelligence including a transmission line extending 115

- from a transmitting station to a receiving station, means for impressing wave form current upon the line at the transmitting station, a plurality of receiving devices at the receiving station, a number of electro-magnetic devices at the receiving station operable in succession, each receiving device being controllable by a selected plurality of electro-magnetic devices, a line relay unresponsive to the normal current waves and responsive to current of modified wave form and operable upon wave modification, a plurality of additional relays, one corresponding to each electro-magnetic device and operable by the line current whether the waves are modified or unmodified, each of the latter relays being responsive to a particular wave of the series of waves of line current, and therefore being operable in succession, each of said additional relays being adapted to coöperate in turn with the aforesaid line relay when said line relay is operated to effect the operation of the electro-magnetic device associated therewith, the additional relays having armature switches successively actuated by successive current waves, said armature switches being in serial relation with each other, each armature switch being normally separated from the next armature switch and being connected therewith upon actuation, the magnets of said electro-magnetic devices being normally in circuit relation with the armature switch of the relay associated therewith, said line relay serving to complete the energizing circuit for a selected electro-magnetic device, locking circuits established by the operated electro-magnetic devices through the electro-magnets thereof, means for opening the closed locking circuits after the selection of an electro-magnetic responsive device, the armature switch of each relay associated with a selected electro-magnetic device serving to open the energizing circuit as a result of the operation of said armature, means for holding the armature of each selected electro-magnetic device to the position to which it has been moved, and means for releasing said armature.
32. A system of transmitting intelligence including a transmission line extending from a transmitting station to a receiving station, means for impressing alternating current upon the line at the transmitting station, a plurality of receiving devices at the receiving station, a number of electro-magnetic devices at the receiving station operable in succession, each receiving device being controllable by a selected plurality of electro-magnetic devices, a line relay unresponsive to the normal current waves and responsive to current of modified wave form and operable upon wave modification, and a plurality of additional relays, one corresponding to each electro-magnetic device and operable by the line current whether the waves are modified or unmodified, each of the latter relays being responsive to a particular wave of the series of waves of line current, and therefore being operable in succession, each of said additional relays being adapted to coöperate in turn with the aforesaid line relay when said line relay is operated to effect the operation of the electro-magnetic device associated therewith.
33. A system of transmitting intelligence including a transmission line extending from a transmitting station to a receiving station, means for impressing alternating current upon the line at the transmitting station, a plurality of receiving devices at the receiving station, a number of electro-magnetic devices at the receiving station operable in succession, each receiving device being controllable by a selected plurality of electro-magnetic devices, a line relay unresponsive to the normal current waves and responsive to current of modified wave form and operable upon wave modification, a plurality of additional relays, one corresponding to each electro-magnetic device and operable by the line current whether the waves are modified or unmodified, each of the latter relays being responsive to a particular wave of the series of waves of line current, and therefore being operable in succession, each of said additional relays being adapted to coöperate in turn with the aforesaid line relay when said line relay is operated to effect the operation of the electro-magnetic device associated therewith.

- ing station, a number of electro-magnetic devices at the receiving station operable in succession, each receiving device being controllable by a selected plurality of electro-magnetic devices, a line relay unresponsive to the normal current waves and responsive to current of modified wave form and operable upon wave modification, a plurality of additional relays, one corresponding to each electro-magnetic device and operable by the line current whether the waves are modified or unmodified, each of the latter relays being responsive to a particular wave of the series of waves of line current, and therefore being operable in succession, each of said additional relays being adapted to coöperate in turn with the aforesaid line relay when said line relay is operated to effect the operation of the electro-magnetic device associated therewith, locking circuits established by the operated electro-magnetic devices through the electro-magnets thereof, and means for opening the closed locking circuits after the selection of an electro-magnetic responsive device.
34. A system of transmitting intelligence including a transmission line extending from a transmitting station to a receiving station, means for impressing wave form current upon the line, means for effecting individual wave modification, one group of responsive devices coöperatively related with the line, a second group of responsive devices, means for bringing the second set of responsive devices into operative association with the line, said means being responsive to a modified current wave, selecting mechanism at the receiving station for selecting responsive devices from among the groups of responsive devices, and selecting means at the transmitting station for effecting the operation of the selecting mechanism at the receiving station.
35. A system of transmitting intelligence including a transmission line extending from a transmitting station to a receiving station, means for impressing wave form current upon the line, means for effecting individual wave modification, one group of responsive devices coöperatively related with the line, a second group of responsive devices, a third group of responsive devices, apparatus for bringing the second and third groups of responsive devices into operative association with the line, said apparatus being responsive to modified current waves, selecting mechanism at the receiving station for selecting responsive devices from among the groups of responsive devices, and selecting means at the transmitting station for effecting the operation of the selecting mechanism at the receiving station.
36. A system of transmitting intelligence including a transmission line extending from a transmitting station to a receiving station, means for impressing wave form current upon the line, means for effecting individual wave modification, one group of responsive devices coöperatively related with the line, a second group of responsive devices, a third group of responsive devices, apparatus for bringing the second and third groups of responsive devices into operative association with the line, said apparatus being responsive to modified current waves, selecting mechanism at the receiving station for selecting responsive devices from among the groups of responsive devices, and selecting means at the transmitting station for effecting the operation of the selecting mechanism at the receiving station and for modifying selected waves of line current.
37. A system of transmitting intelligence including a transmission line extending from a transmitting station to a receiving station, means for impressing alternating current upon the line, means for effecting individual wave modification, one group of responsive devices coöperatively related with the line, a second group of responsive devices, means for bringing the second set of responsive devices into operative association with the line, said means being responsive to a modified current wave, selecting mechanism at the receiving station for selecting responsive devices from among the groups of responsive devices, and selecting means at the transmitting station for effecting the operation of the selecting mechanism at the receiving station.
38. A system of transmitting intelligence including a transmission line extending from a transmitting station to a receiving station, means for impressing wave form current upon the line, means for effecting individual wave modification, one group of responsive devices coöperatively related with the line, a second group of responsive devices, means for bringing the second set of responsive devices into operative association with the line, said means being responsive to modified current waves, selecting mechanism at the receiving station for selecting responsive devices from among the groups of responsive devices, and selecting means at the transmitting station for effecting the operation of the selecting mechanism at the receiving station and for modifying selected waves of line current.
39. A system of transmitting intelligence including a transmission line extending from a transmitting station to a receiving station, means for impressing wave form current upon the line, means for effecting individual wave modification, one group of responsive devices coöperatively related with the line, a second group of responsive devices, a third group of responsive devices, apparatus for bringing the second and third groups of responsive devices into operative association with the line, said apparatus being responsive to modified current waves, selecting mechanism at the receiving station for selecting responsive devices from among the groups of responsive devices, and selecting means at the transmitting station for effecting the operation of the selecting mechanism at the receiving station.

with the line, said apparatus being responsive to modified current waves, selecting mechanism at the receiving station for selecting responsive devices from among the 5 groups of responsive devices and responding to current of modified wave formation, and selecting means at the transmitting station for effecting the operation of the selecting mechanism at the receiving station and for 10 modifying selected waves of line current.

40. A system of transmitting intelligence including a transmission line extending from a transmitting station to a receiving station, means for impressing alternating current 15 upon the line, means for effecting individual wave modification, one group of responsive devices co-operatively related with the line, a second group of responsive devices, means for bringing the second set of responsive devices into operative association with the line, said means being responsive to a modified current wave, selecting mechanism at the receiving station for selecting responsive devices from among the groups of responsive 20 devices and responding to current of modified wave formation, and selecting means at the transmitting station for effecting the operation of the selecting mechanism at the receiving station.

30. 41. A system of transmitting intelligence including a transmission line extending from a transmitting station to a receiving station, means for impressing alternating current upon the line, means for effecting individual 35 wave modification, one group of responsive devices co-operatively related with the line, a second group of responsive devices, a third group of responsive devices, apparatus for bringing the second and third groups of responsive 40 devices into operative association with the line, said apparatus being responsive to modified current waves, selecting mechanism at the receiving station for selecting responsive devices from among the

groups of responsive devices and responding 45 to current of modified wave formation, and selecting means at the transmitting station for effecting the operation of the selecting mechanism at the receiving station and for modifying selected waves of line current.

50

42. A system of transmitting intelligence including a transmission line extending from a transmitting station to a receiving station, a series of relays operating in succession and each serving to cause the impression of a 55 current wave upon the line and together the impression of waves in fixed order, means for effecting modification of normal wave formation, and electro-magnetic responsive apparatus at the receiving station.

66

43. A system of transmitting intelligence including a transmission line extending from a transmitting station to a receiving station, means for impressing wave form current upon the line at the transmitting station, a plurality of receiving devices at the receiving station, a number of electro-magnetic devices at the receiving station operable in succession, each receiving device being controllable by a selected plurality of electro-magnetic devices, a line relay at the receiving station unresponsive to normal wave form current and responsive to modified wave form current, means for successively bringing said line relay into association with the electro-magnetic devices and serving each time it is operated to cause actuation of the electro-magnetic device with which it is associated, and means at the transmitting station for effecting modification of selected 70 waves.

75

In witness whereof, we hereunto subscribe our names this 11th day of June A. D., 1909.

GEORGE C. CUMMINGS.
JOHN A. KICK.
